UNITED STATES PATENT OFFICE.

ALFONS MAUSER, OF COLOGNE-MARIENBURG, GERMANY.

CLOSURE FOR RECEPTACLES.

Application filed November 22, 1924. Serial No. 751,526.

This invention relates to removable closures for receptacles and particularly to sheet metal barrels or drums used as shipping or storage containers. When such receptacles are used for shipping, it is essential that the removable closures be provided with locking means for securely locking said closures in closed position so that accidental displacement thereof can not occur in the handling and transportation of the receptacle, while for storage it is desirable to provide locking means which, while maintaining the closure in securely locked position, may be readily manipulated to permit the closure to be easily removed at will.

The principal object of the present invention is to provide a new and improved construction of a receptacle closure including a plurality of locking means adapted to be interchangeably used to fulfill the above requirements. A further object is to so construct the closure and the locking means therefor that danger of leakage about the points of connection of the locking means to the closure is prevented. Other objects will appear more fully from the following more detailed description and by reference to the accompanying drawings, showing various illustrative examples of my invention. In said drawings, Fig. 1 is a fragmentary vertical section of a receptacle closure and a locking ring therefor; Fig. 2 is a fragmentary plan view of the cover shown in Fig. 1 showing a different construction of the closure seating members and illustrating the manner in which a pivoted locking means may be interchangeably used, Fig. 3 is a view similar to Fig. 1 showing an application of my invention to a different form of cover seating ring, and Fig. 4 is a view similar to Fig. 1 showing a slightly modified form of the pivoted locking means.

As shown in Fig. 1, the receptacle A has its side wall portion 10 bent to form a lap joint 11 with a sheet metal supporting ring 12, said ring forming a support for a cover seating ring 13. The latter, in the example shown, is channel-shaped in cross section, the lower flange 14 of the channel, in the illustrated example, extending inwardly beyond the upper flange 15 thereof. The inner edge of the supporting ring 12 is bent backwardly about the inner edge of the lower flange 14, said supporting ring 12 cooperating with the horizontal flange 16 of an outer

reinforcing ring 17 to hold the cover seating ring 13 securely in position.

The cover 18 is preferably constructed of two sheets 19 and 20 spaced from each other to form a chamber 19^a and connected together adjacent to their outer edges by any suitable means such as a lap joint, the outer periphery of the cover being formed to provide a horizontally extending marginal flange 21, the arrangement being such that at least one of said sheets is shaped to form an annular flange 22 depending from the inner edge of the marginal flange 21. If desired, a protective annular flange 23 may surround and project below the flange 22, said flange 23 in such case being fastened in place by the aforesaid lap joint. When the cover is in position on the receptacle, the flange 23 projects downwardly beyond the cover seating ring; it will be understood, however, that the provision of this flange 23 is not essential. The upper sheet 19 has formed therein, adjacent to the vertical flange 22, an annular groove 24 in which the vertically extending flange 25 of a locking ring 26 is adapted to be engaged. The locking ring 26 is of angular cross section and has a horizontal flange 26^a which is adapted to be inserted under the upper flange 15 of the cover seating ring and serves to hold the marginal flange 21 of the cover pressed tightly against a packing 27 which rests upon the lower flange 14 of the cover seating ring 13. The locking ring 26 is split at any suitable point of its circumference and is adapted to be forced into locked position, to hold the cover securely in position. When the locking ring is sprung into locked position, accidental displacement thereof is practically impossible, as it is necessary to use a suitable tool to jimmy the ring out of said locked position. Therefore it is desirable, when the receptacle is used for storing materials to which access is desired at frequent times, to provide the closure with locking means which may be more readily disengaged. For this purpose, a plurality of latches 28 are pivotally secured as by the rivets 29 to the upper sheet 19 of the closure.

One end of these latches may be provided with a finger ring 30 for facilitating the manipulation thereof, the other end of the latch being adapted, when the latch is swung at right angles to the position shown in Fig. 2, to engage under the upper flange 15 of the

cover seating ring and thereby lock the closure in its operative position on the receptacle. In the preferred form, that end of each latch 28 which is adapted to pass beneath the flange 14 is bevelled as indicated at 31. If desired, stops 32 may be provided upon the closure, for instance by stamping out the sheet 19 at the proper points, to arrest the swinging movements of said latches 28 toward inoperative positions.

In Fig. 3, the cover seating ring 13^a is constructed of sheet metal and is thus slightly different from that of the ring 13 shown in Fig. 1. The outer edge of the cover seating ring 13^a is connected by a lap joint 11^a with the side wall of the receptacle 10^a. The ring 13^a is provided with an upwardly projecting bead 33 which cooperates with the horizontal flange 16^a of the outer reinforcing ring 17^a to form a channel in which the ends of the latches 28 may be engaged or in which the horizontal flange 26^a of the locking ring may be inserted. The construction of the cover shown in Fig. 3 is identical with that shown in Fig. 1.

While it is preferable to extend the rivets 29 by means of which the latches 28 are secured to the cover, only through the upper sheet 19, so that if the rivet should become loosened leakage is prevented, it will be understood that in certain cases it may be desirable to extend the rivets through both of the sheets 19 and 20 of the cover.

In Fig. 4, I have shown a construction in which the latches 28^a are located on the interior face of the cover so that when the latch is swung to locking position, it will engage under the lower flange 14 of the cover seating ring in Fig. 1 or its equivalent in Fig. 3; it will be understood that in such case the latches 28^a are fixed upon stems 29^a which project through both sheets 19 and 20 of the closure and beyond the upper sheet 19; the projecting ends are provided with handles 30^a accessible from the exterior of the closure for manipulating said latches. The construction of the form shown in Fig. 4 may otherwise be identical with that shown either in Fig. 1 or Fig. 3.

In all of the forms of my invention, the latches when in operative positions, securely lock the closure or cover in its closed position, said latches being easily adjustable to inoperative positions in which the closure or cover is released and thus capable

of being readily removed at will to expose the interior of the receptacles. It will be understood that such latches when in their inoperative positions do not interfere with the use of the locking ring.

It will be understood that various changes and modifications in the specific forms shown and described may be made within the scope of the claims without departing from the spirit of my invention.

I claim:

1. In a receptacle closure, a cover comprising an inner sheet and an outer sheet secured together adjacent to their marginal edges with the intermediate portions of said sheets in spaced relationship from each other, a plurality of locking latches and means for securing said latches to said outer sheet only, whereby leakage about said securing means is prevented by said inner sheet.

2. The combination with a receptacle having an open end, and a pair of horizontally extending flanges spaced one above the other at said open end, the lower of said flanges extending inwardly of the upper flange to form a support for a cover, of a cover having a horizontally extending peripheral flange adapted to be supported by said lower flange and to close said open end, said cover having pivotally secured thereto a plurality of latches for temporarily securing it in closed position, said latches being freely movable upon their pivots into and out of locked engagement with the under side of said upper flange, a split locking ring engageable with said upper flange and said cover and movable into and out of locked engagement therewith only by the use of a leverage exerting tool, said pivoted latches when swung to full unlocked position providing sufficient clearance space to permit the engagement of said split locking ring with said upper flange and cover, whereby either said pivoted latches or said split locking ring respectively may be interchangeably employed with the said cover and upper flange for temporarily locking said cover in closed position for storage purposes or for more permanently locking it in closed position for shipping purposes.

In testimony whereof I have hereunto set my hand.

ALFONS MAUSER.
